UNITED STATES PATENT OFFICE.

WILHELM EDUARD ERICH HABANN, OF BERLIN, GERMANY.

THERMIONIC TUBE.

Application filed June 15, 1922, Serial No. 568,551, and in Germany June 24, 1921.

- Applications have been filed in Germany partly on 24th June 1921 and partly on 14th October 1921, Italy partly on 12th May 1922 and partly on 13th May 1922, France 8th May 1922, Switzerland 10th May 1922, the Netherlands 11th May 1922, Austria and Sweden 12th May 1922, Hungary 15th May 1922, Belgium 17th May 1922 and Denmark 20th May 1922.
- 10 This invention relates to a thermionic tube, in which the path travelled by the electrons between the source of the electrons (filament) and the anode, is acted on in such a manner by at least one constant magnetic field and by at least one constant electric field, which opposes the magnetic field as regards its action on the free electrons, that the path, over which the discharge takes place, acts as a negative resistance. The auxiliary field 20 may be produced by an auxiliary flow of electrons, which is generated by an auxiliary discharge crossing the main discharge and passing between a filament and an anode. A thermionic tube of this type is adapted to be used for all purposes, where it is of advantage, for the path, over which the discharge takes place, to have a negative resistance, for instance for producing, reinforcing, or amplifying, rectifying, etc., alternating currents 30 and oscillations.
- The accompanying drawing shows a constructional example of the invention.
- Figure 1 is a front elevation of the thermionic tube,
- 35 Figure 2 a side elevation and
- Figure 3 a section through the tube on the line 3—3 of Figure 2.
- Figure 4 is a diagram of connections of the thermionic tube shown in Figures 1-3, for use as a generator for oscillations.
- 40 Figures 5 and 6 are diagrams of two modified systems of connections according to the invention.
- The thermionic tube according to Figs. 45 1-3, which is evacuated to such an extent that no perceptible ionization, that is, no glow discharge occurs at the source of the electrons, contains the usual filament 1 and a plate-shaped anode 2. In order to facilitate the emergence from the filament, the latter can be surrounded by a grid 3 of a well-known type, which is connected up to a low positive voltage. Substantially parallel to the path, 50 over which the discharge takes place, there is a metal surface 4, which serves the purpose of producing a constant electric field. In the example shown this metal surface 4 consists of a plate, which is parallel to the path, over which the discharge takes place, and has about the same length as the said path. Perpendicular to the electric field is a magnet 5, for instance an electromagnet, the lines of force of which are perpendicular to the direction of the electric field of the plate 4. Both fields are themselves perpendicular to the direction of motion of the electrons from the filament 1 to the anode 2. They act in opposition to one another with respect to the moving electrons. To obtain this effect it is naturally only necessary for the two fields 60 to have such a relative position that the forces exerted by both on the electrons form a resultant at right angles to the path, over which the discharge takes place.
- Both the electric field and the magnetic field exert under certain conditions a deflecting action on the electrons moving in the path, over which the discharge takes place. Each of these deflections itself constitutes a lengthening of the path of the electrons. On 70 the tube being put into operation, it is so adjusted, that the two fields balance each other, in other words, that the path of the electrons substantially follows a straight line between the filament and the anode.
- 80 Figure 4 shows a diagram of connections, where the tube is used as a generator for oscillations. The oscillatory circuit 6 lies between the cathode 1 and the anode 2. The high voltage battery 7, of about 200 volts, is connected up in the branch circuit between the oscillatory circuit 6 and the anode 2. The electric field of the plate 4 is produced by a battery 8 of about 100 volts, the other pole of which is connected to the cathode 1. The electromagnet 5 is supplied by a constant current of any kind, which may be taken from the battery 9 of the filament.
- The electron-current having a velocity v will thus be subjected to the action of a constant electric field F , and a constant magnetic field H . Owing to the opposite adjustment, one force will deflect the electrons to one side, and the other force to the other side. The deflection due to the electric force is proportional to $\frac{F}{v^2}$, and that due to the magnetic force is proportional to $\frac{H}{v}$. Together with the increasing voltage, which increases v , the deflection due to the magnetic force

will predominate, since this is only inversely proportional to the first power of v , while the deflection due to the electric field is inversely proportional to the second power of v . Therefore the electrons will be deflected from their paths with the increase of voltage; less electrons will arrive at the anode, and the conditions prior to the increase of voltage are destroyed, whereby the anode current decreases when the voltage increases. This is the characteristic of a thermionic tube having a negative resistance, or a falling characteristic.

The said increase in voltage is effected periodically during very short periods of time by the oscillatory circuit 6 cooperating with the anode current as is well known.

The increase in the length of the path of the electrons causes a drop in the strength of the field of the anode as is well known. The increase of the anode voltage had of course previously caused an increase in the strength of field of the anode. The tube can be easily constructed in such a manner that the reduction in the strength of field of the anode, due to the deflection of the electrons, shall be greater than the previous increase in the strength of field, due to the increase in the voltage. The protective grid 3, which is connected for instance to a battery 10 of from 10 to 30 volts, does its share in bringing about the desired effect.

Besides being used as a generator for oscillations, the thermionic tube can also be used as an amplifier. In this case the oscillatory circuit 6 is replaced by the positive resistance to be counteracted, for instance, a telephone line. If the amplified currents are to be connected to a grid, either the grid 3, already mentioned, or a controlling member located next to the said grid and extending into the path of the discharge can be used. The amplification in this case exceeds considerably that of the normal thermionic tubes having three electrodes, as the positive resistance of the telephone, which takes the place of the oscillatory circuit 6, is compensated by the negative resistance of the tube.

If, in place of the microphone currents high frequency receiving currents are connected to the grid or controlling member, the thermionic tube will at the same time act as a rectifier. If an oscillatory circuit is connected up in series with the telephone, it will act as an ultraaudion.

In the modified systems shown in Figures 5 and 6 the action of the thermionic tube is further improved therein that the electric field, which in the constructional form shown in Figures 1-3 is a static field, is converted into a kinetic field. For this purpose the auxiliary field is produced by an auxiliary flow of electrons, which is generated by an auxiliary discharge crossing the main discharge and passing between a filament and

an anode. The lateral electrons thus generated and flying at right angles to the main flow of electrons, force the former ones out of their path, with the result that in this way the conditions for the production of a negative characteristic are more energetically obtained.

As in the constructions described with reference to Figures 1-3 discharge takes place between the cathode 1 and the anode 2. The former can be embraced by a protective grid 3. The magnetic field is generated by an electromagnet coil 5 which is indicated by a dot and dash circle.

According to the modifications shown in Figures 5 and 6 opposite the lateral plate 4, which here represents the anode of an auxiliary discharge, a second filament 14 is mounted between these two electrodes, there is a flow of electrons which crosses that of the main discharge between 1 and 2. The impact of these lateral electrons depends on their number and their velocity. The latter can be varied at will by altering the voltage between the auxiliary electrodes. The number of auxiliary electrons can be increased by varying the dimensions of the filament of the auxiliary cathode. The auxiliary cathode 14 is preferably also surrounded by a protective grid 15.

Fig. 5 shows an arrangement for the generation of oscillations, assuming for the time being the telephone 18 to be short-circuited. The filament 1, which is heated by the battery 9, is connected to the anode 2 by way of the oscillatory circuit 6 and the high voltage battery 7. The oscillatory circuit 6 is coupled to the antenna 19. The auxiliary cathode 14, which is heated by the battery 17, is connected to the auxiliary anode 4 by way of the battery 8. The protective grid 3 is positively charged by a battery 10 and the protective grid 15 by a battery 16. The generator acts in exactly the same manner as that described with reference to Figures 1-3, except that the conditions of the negative characteristic are, in consequence of the more pronounced action of the electric field, formed by the flow of the auxiliary electrons.

On the telephone 18 being connected up, the arrangement acts as a receiver for undamped oscillations arriving in the antenna, that is, as a heterodyne receiver.

The main anode 2 is preferably edge-on to the direction of the corresponding discharge path, which results in the advantage, that the two electron paths cut each other in a much more defined line.

The arrangement shown in Fig. 6 has proved particularly useful. In this arrangement the antenna 19 is not coupled to the oscillatory circuit 6, but to a coil 20, one end of which is connected to a condenser 21. A high resistance 22 is in parallel with the latter. The coil 20 is on the one hand connected

directly either to a controlling grid of the main discharge lying either before or behind the protective grid 3, or to a controlling grid of the auxiliary discharge and is on the other hand connected by way of the condenser 21 to the corresponding cathode. The controlling grids at the main discharge are marked 23 and 24, while those of the auxiliary discharge are marked 25 and 26. Thus the terminal W of the coil 20 is connected to the point R and the terminal V to the points H or P or the terminal W to A and the terminal V to B or C.

In one case the auxiliary electrons and in the other case the main electrons are controlled and the undamped oscillations are modulated to suit the speaking.

I claim:

1. Means for producing negative resistance, comprising a tube having an anode and a cathode between which a stream of electrons may pass, and means for producing adjacent the path of the electrons a constant electric field, and means for producing an electromagnetic field, said fields to be perpendicular to one another and to the direction of the electron stream, said fields being poled and proportional to equally oppose one another at a certain potential on the anode, and to unequally oppose one another at higher potentials on the anode, to deflect the electron stream thereby decreasing the number of electrons that reach the anode for producing the desired negative resistance characteristic.
2. Means for producing negative resistance, comprising a tube having an anode and

a cathode between which a stream of electrons may pass, and an auxiliary electrode positioned at the side of the path of said stream for creating a constant electrostatic field in the path of said electrons and perpendicular to said path, and means for producing a constant electromagnetic field in opposed relation to the static field being of such relative value as to have substantially no deflecting effect upon the electron stream at a certain potential on the anode, but having an unequal deflecting effect upon said stream at higher potentials on the anode, to bend the electron stream away from its path, and reduce the current accordingly.

3. Means for producing negative resistance characteristic comprising a tube, a cathode and an anode in the tube between which a stream of electrons may pass, a grid positioned in the path of said stream of electrons, means comprising an electrode positioned laterally of said path to produce adjacent thereto a constant electrostatic field, transverse in direction to said electron stream, means including a magnet to produce adjacent said path a constant magnetic field, transverse in direction to said electron stream, said electromagnetic field equally opposing the action of said electrostatic field on the electron stream at a certain potential on the anode and unequally opposing said action at a higher potential on the anode to deflect a portion of said electron stream to reduce thereby the current at said higher voltage resulting in the negative resistance characteristic.

WILHELM EDUARD ERICH HABANN.
